Assistant Examiner — Lillian Embrey

(57) **CLAIM**

The ornamental design for a thermometer as shown and described.

DESCRIPTION

1. Thermometer
- 1.1: Front perspective view
- 1.2: Back perspective view
- 1.3: Front view
- 1.4: Back view
- 1.5: Left view
- 1.6: Right view
- 1.7: Top view
- 1.8: Bottom view
- 1.9: Cross sectional view
- 1.10: Cross sectional view

Fig. 1.9 is a cross-sectional view taken along line 9-9 of Fig. 1.3; Fig. 1.10 is a cross-sectional view taken along line 10-10 of Fig. 1.3; the broken lines illustrate portions of the thermometer which form no part of the claimed designs.
